CLAIM

The ornamental design for a foot peg for a motorcycle or an all terrain vehicle, as shown and described.

DESCRIPTION

FIG. 1 is a top frontal perspective view of the foot peg with mounting lugs shown to the left and a foot retainer shown to the right;

FIG. 2 is a top plan view with mounting lugs shown to the left;

FIG. 3 is a front elevation view with mounting lugs shown to the left;

FIG. 4 is a bottom view with mounting lugs shown to the left and the foot retainer shown to the right;

FIG. 5 is a rear elevation with mounting lugs to the right and a foot retainer to its left;

FIG. 6 is an end view looking from the foot retainer end;

FIG. 7 is an end view looking from its mounting lug end;

FIG. 8 is an enlarged top view of a section of the foot peg showing a serrated upper surface of the foot peg with interstitial areas that have curved and beveled surfaces; and, FIG. 9 is an enlarged side view of a section of the foot peg showing a serrated upper surface of the foot peg with interstitial areas that have curved and beveled surfaces.
